COUNTER

Raymond H. Devanney, Berlin, Conn., assignor to
Veeder-Root Incorporated, Hartford, Conn., a
corporation of Connecticut

Application November 18, 1950, Serial No. 196,409

6 Claims. (Cl. 235—131)

1

This invention relates to a register and more specifically to a counter mechanism which may be applied to many installations, whether the operations to be counted occur at relatively high or low frequencies.

The invention particularly concerns counters having a plurality of counter wheels intermittently driven by means engaging the wheel of lowest order, and in accordance with the features of the present invention the driving means can be operated at high speed without causing the wheel of lowest order to overrun and the counter wheels cannot be overthrown while being reset. It is an object of this invention to provide counting mechanism which cannot be overrun while the counting operation is in progress and which cannot be overthrown when the mechanism is reset. Included in this object is the aim of providing an improved, simplified and inexpensive register of this type which can be used as a many purpose counter.

Other objects will be in part obvious, and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawings:

Fig. 1 is a front elevational view of a counter having driving means constructed in accordance with this invention, showing the case or housing in partial section to more clearly reveal the operating mechanism of the counter.

Fig. 2 is a transverse, vertical, cross-sectional view taken as indicated by the line 2—2 of Fig. 1 and viewed in the direction of the arrows;

Fig. 3 is a view similar to Fig. 2 but showing the elements of the drive mechanism as disposed during a counting movement; and

Fig. 4 is a perspective view of a U-shaped arm associated with the drive mechanism to prevent overthrow of the counter wheel of lowest order.

As shown in detail in the drawings, the reference numeral 10 indicates a case or housing which provides a protective cover for the counter mechanism indicated generally by the reference numeral 11. The counter mechanism 11 is supported on a rectangular base 12 which has a pair of integrally formed, vertically arranged end supports 13. The supports or frame members 13 journal a reset shaft 14, a drive shaft 15 and a transfer pinion shaft 16 in parallel relation. An additional vertically arranged frame 17 is spaced in-

2

wardly from the righthand end of the base 12 to provide an additional journal for the transfer pinion shaft 16.

For the most part the counter mechanism 11 is conventional, being made up of elements well known in the art, which for the purposes of the present description are referred to without particularity. A plurality of counter wheels 20 are mounted for rotation about the reset shaft 14 and each counter wheel is associated with a transfer driving gear 21 and a driven gear 21a. The driving gear 21 of one wheel 20 is interconnected to the driven gear 21a of the wheel of next highest order by mutilated pinions (not shown) carried by the transfer pinion shaft 16. The counter wheel 20 of lowest order is disposed farthest to the right as viewed in Fig. 1 and is intermittently driven by the drive mechanism to be described presently. The remaining counter wheels are driven from the wheel of lowest order in conventional step by step fashion through the transfer wheels 21 and the previously mentioned mutilated pinions. The digits on the number wheels 20 can be read through a window 22 provided in the casing 10 and the number wheels can be reset through a manually operable key 23 connected to the reset shaft 14. Reset is effected by turning the shaft in the same direction in which the counter wheels turn during the counting operation.

The counter wheels 20 are individually picked up by the reset shaft 14 for rotation therewith so that they will be aligned at reset for a "0" reading through the window 22. Of course the number wheels normally rotate about the reset shaft 14 when being driven through the previously mentioned driving gears and driven gears. During reset the driving and driven gears do not move with the reset shaft.

The drive shaft 15 for the counter mechanism 11 may be connected in any suitable manner for rotation by the machine or other device, the operations of which are to be counted. The shaft 15 is secured against axial movement by means of a thrust bearing 25 secured thereto and which abuts an annular boss 26 on the righthand journal support 13. A multiple cam, indicated generally by the reference numeral 27, is supported for rotation with shaft 15. A collar 28 embracing the shaft 15 spaces the cam 27 inwardly from the righthand support 13. The cam 27 has spaced cam plates 29 and 30 separated by center portion 31. Cam plates 29 and 30 are similarly shaped, each having radially greater and lesser follower engaging portions which engage cam followers 35 and 36, respectively, car-

ried by a ratchet actuating member 37. The plates 29 and 30 are arranged on shaft 15 so that, as the radially greater portion of the plate 29 engages follower 35, the radially lesser portion of plate 30 will engage follower 36, and vice versa.

Ratchet actuating member 37 is shaped like a bell crank having two angularly related arms 38 and 39 pivoted on the transfer pinion shaft 16 at the apex of the angle between the arms. Arm 38 is generally horizontally disposed and carries cam roller 35 and arm 39 projects generally vertically downwardly and carries cam roller 36. Rotation of drive shafts 15 and cam 27 will cause reciprocating clockwise and counterclockwise movement of the actuating member 37 about the transfer shaft 16 by engagement of cam plates 29 and 30 with the rollers 35 and 36.

A generally U-shaped member 60 is mounted for pivotal movement about the transfer shaft 16 and has angularly related legs 61 and 62. The member 60 is axially spaced from actuating member 37 with its leg 61 substantially parallel to arm 38 and secured thereto at its end by a pin 63. The operation of the member 60 will be described in more detail later, but for the present it can be said that the member 60 reciprocates with the ratchet actuating member 37 in response to movements of cam followers 35 and 36.

A ratchet driving pawl 40, of laminated construction for manufacturing convenience, is pivotally mounted on the pin 63. An arcuate spring 46 has one end secured to a pin 42 held by the arms 38 and 61 with its other end disposed in a depression 43 in the pawl 40 to bias the pawl in a clockwise direction about the pin 63. However, clockwise movement of the pawl 40 is limited by the pin 42 so that the pawl 40 is directed generally upwardly. Clockwise rotation of the rocker 37 will cause the pawl 40 to engage a tooth of a ratchet wheel 45 which is drivingly connected in the usual manner to the transfer wheel 21a associated with the counter wheel 20 of the lowest order. There is one tooth provided on the ratchet wheel for each digit marked on the lowest order number wheel so that, as each tooth of the ratchet 45 is advanced by the pawl 40, there will be a corresponding advance of one digit by the wheel of lowest order. The spring 46, in urging the pawl 40 clockwise, assures positive engagement between the pawl and the ratchet teeth to effect advancing movement of the ratchet wheel 45 during the clockwise movement of the rocker 37. For each reciprocation of the actuating member 37, the ratchet wheel 45 is advanced one step corresponding to an advance of one digit by the number wheel 20 of lowest order.

A stop pawl 50 is journaled about the transfer shaft 16 to engage the ratchet wheel 45 to prevent reverse movement thereof as the drive pawl 40 is disengaged in a wiping motion. The pawl 50 is biased to engagement with the ratchet wheel 45 by an arcuate spring 51 held at one end by a pin 53 disposed between the actuating member 37 and the member 60 and engaging a depression 52 in the pawl 50.

As previously mentioned, the one leg 61 of the member 60 projects in the same direction as the arm 38 on actuating member 37, but the other leg 62 of the member 60 projects in a generally opposite direction to the other arm 39. Each of the legs 61 and 62 has an axially inwardly turned ear 64 and 65, respectively, which are used to block the ratchet wheel 45 against overthrow of the counter wheel 20 of lowest order. When the actuating member 37 is driven clockwise to drive

the ratchet wheel, the ear 64 of leg 61 will be disposed between successive teeth of the ratchet wheel 45 during engagement of the drive pawl 40. Thus positioned, the ear 64 prevents overrunning of the ratchet wheel and number wheel of lowest order. This position of the elements is indicated in Fig. 3.

The ear 65 on the leg 62 is disposed between two adjacent ratchet teeth when the pawl 40 is not in engagement as shown in Fig. 2. During disengagement of the drive pawl 40, the number wheels 20 can be reset. A reset overthrow will occur when, through inadvertence or otherwise, the counter wheel of lowest order is shifted beyond the desired position by one or more digits as though being driven through the ratchet wheel. The overthrow of the number wheel of lowest order is accompanied by movement of the ratchet wheel and transfer gear 21a. Such movement is effectively stopped by the positioning of the ear 65.

Thus, it will be seen that there is provided a register having a counting mechanism of simplified construction which incorporates means for preventing overrunning of the counter wheels during driving operation and which prevents overthrow of the mechanism during the resetting operation. The counter mechanism can thus be applied in a wider range of installations and will not be subjected to inaccuracies at high speeds.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In a counter of the type having counting means including a number wheel of lowest order, a ratchet wheel associated with the number wheel of lowest order, and means for resetting the counting means, a ratchet actuating arm mounted for reciprocal movements in a plane substantially normal to the axis of the ratchet wheel, a drive pawl secured to said actuating arm engageable with the ratchet wheel and operable during movement of the actuating arm in one direction to advance the ratchet wheel one step, first stop means carried by said actuating arm engageable with the ratchet wheel during movement of the actuating arm in said one direction to prevent advance of the ratchet wheel by more than one step, and second stop means carried by said actuating arm engageable with the ratchet wheel during movement of the actuating arm in the opposite direction to impede advance of the ratchet wheel when the counting means is reset.

2. In a counter of the type having counting means including a number wheel of lowest order, a ratchet wheel associated with the number wheel of lowest order, and means for resetting the counting means, a ratchet actuating arm mounted for reciprocal movements in a plane substantially normal to the axis of the ratchet wheel, a drive pawl secured to said actuating arm engageable with the ratchet wheel and operable

during movement of the actuating arm in one direction to advance the ratchet wheel one step, first stop means carried by said actuating arm in spaced relation to said drive pawl and engageable with the ratchet wheel in sequence with said drive pawl during movement of said actuating arm in said one direction to prevent advance of the ratchet wheel by more than one step, and second stop means carried by said actuating arm at the opposite end thereof from said drive pawl and engageable with the ratchet wheel during movement of said actuating arm in the opposite direction to impede advance of the ratchet wheel when the counting means is reset.

3. In a counter of the type having counting means including a number wheel of lowest order, a ratchet wheel associated with the number wheel of lowest order, and means for resetting the counting means, a ratchet actuating arm mounted for reciprocal movements in a plane substantially normal to the axis of the ratchet wheel, a drive pawl secured to said actuating arm engageable with the ratchet wheel and operable during movement of the actuating arm in one direction to advance the ratchet wheel one step, a U-shaped member secured to said actuating arm for reciprocation therewith and having one leg disposed in spaced parallel relation to said actuating arm, said U-shaped member having a second leg angularly related to said first leg, said first leg having an ear engageable with the ratchet wheel during movement of said actuating arm in said one direction to prevent advance of the ratchet wheel by more than one step, and said second leg having an ear engageable with the ratchet wheel oppositely of said first mentioned ear during movement of the actuating arm in the opposite direction to impede advance of the ratchet wheel when the counting means is reset.

4. In a counter of the type having counting means including a number wheel of lowest order, a ratchet wheel associated with the number wheel of lowest order, and means for resetting the counting means, a ratchet actuating arm mounted for reciprocal movements in a plane substantially normal to the axis of the ratchet wheel, a drive pawl secured to said actuating arm engageable with the ratchet wheel and operable during movement of said actuating arm in one direction to advance the ratchet one step, a stop pawl pivotally mounted adjacent the ratchet wheel, spring means carried by said actuating arm urging said stop pawl into engagement with the ratchet wheel to prevent return movements thereof, a U-shaped member secured to said actuating arm for reciprocation therewith, said U-shaped member having one leg disposed in spaced parallel relation to said actuating arm on one side of the ratchet wheel and having an-

other leg disposed at an angle to the first leg on the other side of the ratchet wheel, said first leg having an ear engageable with the ratchet wheel during movement of the actuating arm in said one direction to prevent advance of the ratchet wheel by more than one step, and said second leg having an ear engageable with the ratchet wheel during movement of said actuating arm in the opposite direction to impede advance of the ratchet wheel when the counting means is reset.

5. In a counter of the type having counting means including a number wheel of lowest order, a ratchet wheel associated with the number wheel of lowest order, and means for resetting the counting means, a ratchet actuating arm mounted for reciprocal movements in a plane substantially normal to the axis of the ratchet wheel, a drive pawl secured to said actuating arm engageable with the ratchet wheel and operable during movement of said actuating arm in one direction to advance the ratchet wheel one step, and stop means carried by said actuating arm engageable with the ratchet wheel when said drive pawl is disengaged to impede advance of the ratchet wheel when the counting means is reset.

6. In a counter of the type having counting means including a number wheel of lowest order, a ratchet wheel associated with the number wheel of lowest order, and means for resetting the counting means, a drive shaft, cam means mounted on said shaft for rotation therewith, a ratchet actuating arm pivotally mounted adjacent said cam means and engageable therewith for reciprocating movements in a plane substantially normal to the axis of the ratchet wheel, a drive pawl secured to said actuating arm engageable with the ratchet wheel and operable during movement of the actuating arm in one direction to advance the ratchet wheel one step, a U-shaped member secured to said actuating arm for reciprocation therewith and having one leg disposed in spaced parallel relation to said actuating arm, said U-shaped member having a second leg angularly related to said first leg, said first leg having an ear engageable with the ratchet wheel during movement of said actuating arm in said one direction to prevent advance of the ratchet wheel by more than one step, and said second leg having an ear engageable with the ratchet wheel oppositely of said first mentioned ear during movement of the actuating arm in the opposite direction to impede advance of the ratchet wheel when the counting means is reset.
